United States Patent Office

Des. 229,653
Patented Dec. 25, 1973

229,653

APPLIANCE COVER

Ruth F. Hendrickson, 638 Continental Road,
Hatboro, Pa. 19040

Filed Sept. 27, 1971, Ser. No. 184,320

Term of patent 14 years

Int. Cl. D6—13

U.S. Cl. D6—269

Fig. 1.

Fig. 4.

Fig. 3.

Fig. 2.

FIG. 1 is a perspective view of an appliance cover embodying my new design, the view being from the left-hand side.

FIG. 2 is similar to FIG. 1, the view being from the right-hand side of FIG. 1.

FIG. 3 is an end elevational view of FIG. 1.

FIG. 4 is a top plan view of FIG. 1.

I claim:

The ornamental design for an appliance cover, embodying my new design as shown.
